[57] **CLAIM**

The ornamental design for a combined service station building and canopy, substantially as shown and described.

DESCRIPTION

FIG. 1 is a front elevational view of a combined service station building and canopy with the lower portion of the canopy cut away;

FIG. 2 is a side elevational view thereof from the right side of FIG. 1 with a portion of the canopy cut away;

FIG. 3 is a side elevational view thereof from the left side of FIG. 1 with a portion of the canopy cut away;

FIG. 4 is a rear elevational view thereof;

FIG. 5 is an alternative embodiment of another rear elevational view thereof; and

FIG. 6 is a top plan view thereof.

FIG. 1

FIG. 4

FIG. 2

FIG. 6

FIG. 5
